UNITED STATES PATENT OFFICE.

LAWRENCE A. ABBOTT, OF CHICAGO, ILLINOIS.

HEAT-REGULATOR.

1,136,084.

Specification of Letters Patent. Patented Apr. 20, 1915.

Application filed March 31, 1908. Serial No. 424,352.

To all whom it may concern:

Be it known that I, LAWRENCE A. ABBOTT, a citizen of the United States, residing in the city of Chicago, in the county of Cook 5 and State of Illinois, have invented a certain new and useful Heat-Regulator, of which the following is a specification.

My invention relates to that class of devices which is desired to control the admission of a heating fluid to a radiator by the temperature of the room in which the radiator is located, and is more particularly designed for use in those buildings in which the so-called vacuum system of heating is employed, it being so designed that it may be attached to the vacuum side of the radiator, and has for its object to provide certain improvements in construction and operation of the same as will be hereinafter more definitely pointed out and claimed, reference being had to the accompanying drawings in which—

Figure 1, is a view of a room or apartment having my improved invention installed 25 therein. Fig. 2, is a detailed view of my improved fluid pressure valve. Figs. 3, 4, 5, and 6, are detail views of my improved thermostat, and the method of attaching it to the wall.

Similar reference numerals refer to similar parts throughout the entire description.

In the drawings: 1 is the radiator which is provided, at one end, with suitable pipe connections 2 leading to a source of supply 35 (not shown) of the heating medium, 4 is the vacuum valve which is suitably connected to a radiator; 5 is my improved fluid pressure motor which is formed, as better shown in the detailed view, with a motor chamber 6, at the top, in which is located the motor diaphragm 7. This diaphragm has secured to its upper surface a block 8, of wood or other suitable material, and a flanged casting 9 is fitted to the lower side 45 of the wood in the center thereof, the flange of the casting 9 engaging the adjacent face of the diaphragm and it is held in position by means of screws 10, or any other convenient form of fastening. An internally 50 threaded opening 11 is provided in the central portion of the flanged casting 9 and has secured thereto a valve stem 12 the upper end of which is provided with threads fitting to and coinciding with the threads in 55 the flanged casting. A lock nut 13, or any other convenient means for locking the valve

stem in position, may be used. The lower end of the stem carries a valve 14 adapted to engage the valve seat 15. It is well known that these valves give considerable trouble by reason of wear, and it is a considerable source of annoyance to engineers that they have to disconnect the entire pipe connections in order to remove the valve for the purpose of putting in a new valve, or of 60 grinding the old one into its seat. My valve casing 17 is constructed with an opening 16 in the bottom thereof of slightly larger diameter than the valve, the opening being provided with a plug 18, which may be provided with a shoulder to which a wrench 65 may be attached or may be slotted for a screw driver. It is obvious from the above description that all that it is necessary to do in making a repair of this valve is to remove the plug 18, loosen the lock nut 13, and by unscrewing the valve stem, it can be 70 taken out through the bottom of the valve casing without breaking a single joint. A coil spring 19 is located in the upper part 75 of the chamber 6 and exerts a pressure 80 against the upper side of the block 8. The upper part of the motor chamber 6 is connected by means of suitable pipe connections 20 to the interior of my improved thermo- 85 stat 21, which is constructed, as better shown in the detail views, of a base 22, which is provided with lugs 23 and 24, a passage 31 being provided in the lug 23 which leads to the interior of the thermostat 21. Suitable 90 pipe connections 32 lead from the opening 29 to the vacuum side of the radiator.

It may be found desirable in practice to locate a check valve 33 between the connection with the vacuum pipe 34 and the thermostat 21. A passage 35 leads through the lug 24 to a chamber 36 formed in the base 22 of the thermostat 21. This chamber 36 is provided with internal threads and has mounted in its inner end a plug 37 which is 100 slotted as at 38 to provide for screw-driver adjustment. An opening 39 is provided through the screw-threaded plug 37 affording a passage to the interior of the thermostat. A pipe plug 40 is fitted to the opposite end of 105 the chamber 36 and effectively seals it from the atmosphere. At the same time it is obvious that by the removal of the plug 40 it is easily possible to regulate the position of the plug 37 with a great degree of nicety. A 110 chamber 41, somewhat similar to the chamber 36, is provided with a plug 42, similar

to the plug 37, it being provided with an opening 43 through its center. A pipe plug 44, having a minute orifice 45 through its center, is provided at the outer extremity of 5 the chamber 41, the orifice 45 leading to the exterior of the thermostat 21. Cotton, or other suitable material, may be located in the chamber 41, to cleanse the air as it enters from the atmosphere to the interior of the 10 thermostat. The thermostat is provided with a metal band 46, which is secured to a band of hard rubber 47, the two being held securely in position by means of screws or bolts 48. It is generally necessary to rivet 15 the hard rubber to the brass very securely, but where it is used as a band, as in my improved thermostat, the one operates to hold the other securely in position and only a slight fastening is necessary. The end 49, 20 of the band, has secured thereto an arm 50, which is mounted in a slot 51, formed in a valve 52, which is mounted upon a pin or pivot 53 and swings thereon. Coil springs 54 may be provided to take up the extra pull, 25 if necessary. The lower end 55, of the valve 52, operates to open and close the openings 39 and 43. A cap 56 is threaded upon the base 22, packing 57 being provided therebetween, in order to make a tight joint. The 30 base 22 is securely attached to the casting 27, by means of screws 58, packings 59 and 60 being provided where the lugs 23 and 24 enter the recesses 25 and 26. This makes it extremely convenient to remove the thermostat, 35 and make any necessary adjustments.

The operation of the device is as follows:—The fluid pressure motor 5 is normally in the position shown in the drawings. When the temperature has raised to a predetermined point the metal band 46 expands, 40 carrying with it the arm 50, which, in turn, moves the valve 52 away from the opening 39, and will cause it to close the opening 43. Since the opening 39 is connected by the 45 pipe connections 32 to the vacuum side of the radiator, it naturally follows that the air contained in the interior of the thermostat is almost instantly exhausted, and the vacuum operates to draw nearly, if not all, 50 of the air out of the pipe 20 and the upper part of the motor chamber 6. This removes the atmospheric pressure from the top of the motor diaphragm 7, and it follows that it is forced upward by reason of the pressure of the atmosphere upon its other side, with the 55 result that the valve 14 is raised and is securely seated upon its seat 15. As soon as the temperature falls it is obvious that the metal band will contract and, acting through 60 the medium of the arm 50 and the valve 52, will move the end 55 of the valve 52 away

from the opening 43 and cause it to close the opening 39. This admits the air through the orifice 45, and the vacuum being relieved, the pressure upon each side of the 65 diaphragm 7 is equal, with the result that the coil spring 19 exerts a pressure sufficient to move the valve stem downwardly, and in turn the valve 14 away from its seat 15, thus permitting the inflow of the heating medium 70 to the radiator. The movement of the valve 52 under the thermostatic action of band 46 in uncovering opening 39 and closing opening 43, shuts off ingress of air to the interior of the thermostat through openings 43 and 75 45, thereby sealing pipe 32 from the atmosphere, so that the constant vacuum in the return pipe 34 will maintain its suction on the radiator 1 while the valve 14 is being operated by said vacuum to seat at 15. It follows, therefore, that by reason of this closing of opening 43 as the opening 39 is uncovered, the action of the vacuum in pipe 34 on the radiator 1 is uninterrupted.

It will be obvious from the above description that my improvement may be attached to any and all heating systems employing the vacuum system, and it becomes possible with a very slight change to provide for a regulation of the inflow of the heating medium by the temperature of the room without having recourse to electricity, with its attending sources of annoyance, or without the use of compressed air with its expensive pipings, etc., including the maintenance of 95 an air compressor.

Many changes may suggest themselves to persons skilled in the art which will fall within the scope of my invention, as claimed.

Having described my invention, what I 100 regard as new and desire to secure by Letters Patent, is:—

In a heat regulator for vacuum systems, the combination with a radiator, of a supply pipe on one side thereof, a single vacuum return pipe on the opposite side in constant communication with said radiator, and through which the air and water of condensation pass, a valve in said supply pipe, a fluid pressure motor for controlling said 110 valve operated through the vacuum, and thermostatically operated means for controlling the communication of the vacuum pipe with said motor, said means operating, as it opens said motor to the action of the vacuum pipe, to seal said pipe from the atmosphere without interrupting the communication of said vacuum pipe with the radiator. 115
